UNITED STATES PATENT OFFICE.

EDWARD J. GOODYEAR, OF WILKINSBURG, PENNSYLVANIA.

AIR-INLET DEVICE FOR EXPLOSIVE-ENGINES.

1,110,922.

Specification of Letters Patent. Patented Sept. 15, 1914.

Application filed December 31, 1913. Serial No. 809,663.

To all whom it may concern:

Be it known that I, EDWARD J. GOODYEAR, a citizen of the United States, and resident of Wilkinsburg, in the county of Allegheny 5 and State of Pennsylvania, have invented certain new and useful Improvements in Air-Inlet Devices for Explosive-Engines, of which the following is a specification.

It is usual practice to so adjust the carbureter of an explosive engine that it will 10 properly proportion the fuel elements to develop maximum power under heavy loads. For automobile engines the carbureter is ordinarily adjusted to develop the highest 15 efficiency for hill climbing or whenever the engine load is greatest. The adjustment is ordinarily made with considerable precision and remains fixed so far as the normal working of the engine is concerned, not being susceptible to change by the operator or driver. 20 When, however, the load is reduced, as for level or smooth running, at which times the throttle is partially closed, the fuel mixture is unnecessarily rich in gasoline and considerable waste results, the desired speed 25 under reduced load being obtainable with less consumption of gasoline if air in proper amount were added to the charges passing to the engine from the carbureter. This is 30 a well recognized condition, and to overcome it various expedients have been proposed, in all of which provision is made for admitting air to the cylinder or intake pipe in addition to the air which enters through the carbureter.

The primary object of the present invention is to provide for automatically admitting the auxiliary air, and for automatically regulating the amount admitted to obtain 40 the highest efficiency in all the partially closed positions of the throttle, so that the fuel elements drawn into the engine will at all times be mixed and proportioned for developing maximum power for the gasoline 45 consumed. To accomplish this the increased cylinder suction resulting when the throttle is more or less closed is utilized to open a spring-closed air-admitting valve, and the tension of the latter is adjustable so that 50 more or less air will be admitted as will best serve the requirements of each engine to which the invention is applied.

Another purpose is to provide for the admission of cold air to the cylinders for 55 braking purposes, as when descending grades, also whenever the speed is to be de-

creased or the car stopped. It is well understood that when air is admitted in this way its compression in the cylinders constitutes a powerful brake, at the same time cooling the engine and clearing it of fouling deposits. This principle is utilized in the present invention by providing a manually operated brake valve and combining therewith the automatic auxiliary valve above referred to, so that both features are contained in one and the same attachment, the brake valve being manually operated and opening outwardly under spring pressure, and the automatic valve inwardly and held normally closed by an adjustable spring. While the best results are produced by attaching the auxiliary valve mechanism to the cylinder intake pipe or manifold, the invention is not limited in this regard so long as the air is effectively admitted to the cylinders.

In the accompanying drawings, Figure 1 is an elevation of an automobile engine with the improved valve mechanism applied to the intake pipe or manifold thereof. Fig. 2 is a longitudinal section, enlarged, of the valve mechanism, and Fig. 3 is an elevation of the same.

Referring to the drawings, 2 designates 85 the intake pipe or manifold of a four-cylinder automobile engine through which the explosive charges are drawn from carbureter 3 to the engine cylinders 4.

5 is the throttle valve.

It will be understood that the engine and carbureter may be of any desired construction or type.

The invention as here embodied consists of an outer shell or casing 6 open laterally 95 at 7 for the admission of air. The casing is formed with valve seat 8, and its reduced extremity 9 is externally screw-threaded for connecting with the engine, in the present instance with intake or manifold 2. The 100 outer end of casing 6 is closed by the screw cap or plug 10, the latter being centrally apertured to pass a tubular stem 11 which is movable longitudinally and rotatable therein and at its inner end carries valve 12 which fits seat 8, a stout spring 13 holding the valve normally seated.

Valve 12 is formed with air passages 14, and the under or inner face of valve 12 constitutes a seat for the inwardly opening 110 automatic valve 15 which is slidable on a stem 16. A portion of the length of this

stem is threaded at 17 and hence adjustable in the internally threaded tubular stem 11. This adjustment serves to regulate the tension of spring 18 confined between the stem 5 head 16' and valve 15. Stem 16 may be turned to either increase or decrease the tension of spring 18 and is secured in the required adjustment by lock nut 19. During this stem-adjusting operation the normally rotatable tubular stem 11 may be temporarily locked by set screw 20 carried by cap 10. A pull device, such as cord or wire 21, may extend from stem 16 for manually opening valve 12 for braking the 15 engine.

For automobile engines the attachment is preferably applied to the manifold above the carbureter and as near as practicable to the manifold fork. It is desirable to have the 20 attachment at least some distance from the carbureter so that the charges may have the full mixing effect of the carbureter. The charge then encounters the air admitted through auxiliary valve 15, and the gaseous 25 portions of the charge are further broken up or disseminated by the added air before entering the cylinders. While for the best results this further disseminating and mixing should take place only after the full 30 effect of the carbureter has been obtained, the auxiliary air must not be admitted in too close proximity to the manifold fork, otherwise there will not be an equal distribution between the forks or branches. With the 35 tension of spring 18 properly adjusted for a given engine, the cylinder suction will operate to open valve 15 whenever throttle 5 is closed sufficiently to so restrict the inflow from the carbureter as to create a suction or 40 partial vacuum of valve opening strength. Obviously, the extent which valve 15 will open and the duration of the open periods will vary with the suction force, and as the latter is in turn controlled by the position 45 of throttle valve 5, more or less auxiliary air will be added to the fuel elements drawn from the carbureter, the admission of auxiliary air being thus automatically and accurately controlled. Valve 15 and its spring 50 tension are in effect integral parts of valve 12 during the opening movement of the

latter and in no way interfere with the braking operation.

I claim:

1. The combination with an explosive engine intake pipe, and a carbureter, of two normally closed valves for admitting air to the intake pipe independently of the carbureter and of each other, one valve adapted to be opened by suction within the pipe, and means for opening the other valve. 55

2. The combination with an explosive engine intake pipe, and a carbureter, of two normally closed valves adapted, respectively, to open inwardly and outwardly for admitting air to the intake pipe independently of the carbureter and of each other, the inwardly-opening valve adapted to be opened by suction within the intake pipe, and means for opening the outwardly-opening valve. 65 70

3. The combination with an explosive engine intake pipe, and a carbureter, of a normally closed valve for admitting air to the intake pipe independently of the carbureter, and a normally closed supplemental valve 75 mounted on the first mentioned valve and adapted to be opened by suction within the pipe for admitting air to the latter independently of said first mentioned valve and independently of the carbureter. 80

4. The combination of an explosive engine intake pipe, a manually operated air-admission valve in communication with the pipe, and an inwardly opening spring-closed air admitting valve mounted on the manually operated valve and adapted to be opened by suction within the pipe. 85

5. The combination with an explosive engine cylinder and a carbureter in communication therewith, of a manually operated air admitting valve in communication with the cylinder independently of the carbureter, and an inwardly opening spring-closed suction operated air admitting valve carried by the manually operated valve. 90 95

In testimony whereof, I affix my signature in presence of two witnesses.

EDWARD J. GOODYEAR.
